UNITED STATES PATENT OFFICE.

CHARLES A. SNYDER, OF POWHATAN HEADQUARTERS, VIRGINIA.

BALL-ACTUATED REGISTERING MECHANISM.

No. 830,186.

Specification of Letters Patent.

Patented Sept. 4, 1906.

Application filed January 27, 1906. Serial No. 298,180.

To all whom it may concern:

Be it known that I, CHARLES A. SNYDER, a citizen of the United States, residing at Powhatan Headquarters, in the county of Powhatan and State of Virginia, have invented certain new and useful Improvements in Ball-Actuated Registering Mechanism, of which the following is a specification.

It is well known that the matter of the selection of jurors is or should be one of absolute impartiality, and it is therefore customary to make elaborate provisions to secure this impartiality.

It is the object, therefore, of my invention to provide a device especially adapted to insure impartiality in the selection of men for jury service, although it may be used for many other useful and desired purposes, and which shall be of extreme simplicity of construction, which shall not be liable to get out of order, and which shall be easy and convenient to operate.

The device also comprehends the provision of means whereby the judge of a court may verify the number of jurors so drawn and recorded by the clerk of the court, a separate registering mechanism being provided for use by the judge in such verification, it being understood that such separate registering mechanism should register the same number of men as is registered or recorded by the mechanism operated by the clerk, the judge being thus enabled to check and to tally the number of jurors so recorded by the clerk of the court.

The device also comprehends the provision of means whereby when more than one list of jurymen are drawn up the judge is enabled to keep a check on the clerk of the court, thus to prevent the clerk from using one list more than once.

With these objects in view and others appearing as the specification proceeds the invention comprehends the novel construction, combination, and arrangement of parts of a device characterized by my invention, as will be hereinafter fully described in the specification, summed up in the claims, and illustrated in the drawings.

In the drawings, Figure 1 is a front perspective of my device. Fig. 2 is a cross-section on line 2 2, Fig. 1. Fig. 3 is a central vertical section through the ball-containing receptacle, its supporting-standards, and the base and looking at the inner face of the rear

section of the depending member carried by the receptacle. Fig. 4 is a rear side elevation of the front section of the depending member, displaying its contained working mechanism and with the plunger in one position. Fig. 5 is a similar view showing the plunger in another position. Fig. 6 is a cross-section on line 6 6, Fig. 4. Fig. 7 is a cross-section on line 7 7, Fig. 5; and Fig. 8 is a detail view of the auxiliary plunger removed from the device. Fig. 9 is a detail view of my funnel removed from the device.

Referring to the drawings in detail, 1 represents a suitable base, preferably of the contour shown in the drawings and desirably having cup-shaped depressions 2 on its upper surface and chambers 3 and 4 therein, the former advantageously having a cover 5, which may be provided with any suitable description of key-lock 6, whereby access may be had to the chamber, and the latter and larger chamber 4 (shown in dotted lines in Fig. 1) may have a normally locked door 82, affording access to the chamber, and an exit-opening provided with a door 79, having 80 a keyhole 7. The base also contains additional small chambers 8 and 9 in proximity to the chamber 4 and adapted for the reception of any form of registering mechanism.

Standards 10, whose feet 11 may be secured to the base 1 by screws 12 or the like, carry at the top, rotatably mounted in bearings therein, a bridge 13. Suitably secured to the bridge 13 is a hollow ball-containing receptacle 14, desirably formed in the shape of a round or oval or other contoured bulb or cylinder and having a top opening 15, with an interiorly-threaded extension 16 surrounding the opening, and formed at the bottom with an internal ledge 17, the receptacle 18 being formed also with a bottom opening 18 therethrough.

It is an important object of my invention to support the ball-containing receptacle 14 in the manner described, so that it is capable of oscillatory or rocking movement, because in the exigency of the balls sticking or wedging in the runway (presently described) the receptacle may be cocked or oscillated, thus shaking up the balls and conducing to restore normal free flow thereof through the runway.

Adapted to rest on the ledge 17 by means of its flange 19 is a removable open-ended funnel 20, which may be formed in any shape

but advantageously tapering from top to bottom, and constructed of spring material and being formed also with longitudinal slots 21, extending from the bottom to a point 5 near the top of the funnel, thus dividing the funnel into prongs, fingers, or tines 22. The bottom open end of the funnel is somewhat smaller than the size of the balls 23, which when it is desired to supply the receptacle 14 therewith are slipped into the top of the funnel and forced through the bottom thereof, the spring prongs or fingers 22 yielding or slightly separating apart or outward and allowing the balls to escape from contact therewith and to fall to the bottom of the receptacle 14, which, with the funnel, thus constitutes a trap for the balls, the funnel by its peculiar conformation preventing withdrawal of the balls by way of the funnel after they have 20 once been passed therethrough.

After the desired number of balls have been inserted in the receptacle, which may be adapted for the reception of any number, but preferably one thousand, a closure-cap 25 is secured within the extension 16 and embodies an externally-threaded lower body 24 and an upper corrugated, ribbed, or roughened finger and thumb hold 25. The cap is also provided with a flange 27, having a per 30 forated offset or lug 28, adapted to register or mate with the ear 29, provided with a perforation 34 and hinged at 30 to link 31, which is in turn hinged at 32 to a plate 33, secured to the extension 16, whereby a cord, ribbon, 35 or the like may be passed through the mating perforations in the lug 28 and the ear 29 and its ends secured by sealing-wax or the like, thus constituting an official seal and closure of the ball-containing receptacle 14, 40 or, if desired, to effect a stronger locking of the ball-containing receptacle 14 a short length of wire may be passed through the openings just mentioned and its ends secured by a slug of solder, all as the exigencies 45 of the particular situation may seem to warrant and to demand or as the wishes and desires of the court may determine. The means described for locking the ball-containing receptacle 14 prevent unauthorized tampering therewith after the balls have been 50 duly inserted therein by the properly-accredited officer of the court. As the sealing-wax and the wire and solder are obvious expedients, I have deemed illustration thereof 55 unnecessary.

Carried by the receptacle 14 and disposed on the under side thereof is a depending member 37, formed in two sections 35 36, secured together in any suitable manner, and 60 the first-mentioned of which sections may be called the "front" and the latter-mentioned of which sections may be called the "rear" sections, and which sections contain the mechanism for effecting contact with the registering mechanism for recording and recording

the number of balls drawn from the receptacle 14.

Interiorly and longitudinally of the member 37 and extending entirely therethrough and registering with the opening 18 of the 70 receptacle 14 is a runway or channel 38, and each section 35 and 36 is advantageously provided with a longitudinal slot 39 therethrough, communicating with the channel 38, glass windows 40, or windows of other 75 transparent material, being secured in the faces of the sections 35 and 36, whereby a view may be obtained of the balls in their transit or passage through the runway 38.

In the walls of the runway 38, near the top 80 thereof, are suitably-disposed pivoted rings 68, sunk in mortises 69, and which when the receptacle 14 is rocked or turned upside down in endeavor to make the balls in the runway reenter the receptacle will swing on 85 their pivots out of the mortises 69, and thus catch the balls and block entrance to the receptacle 14, the rings thus constituting flap or gravity valves, it being understood that I do not confine myself to rings *per se*, as any 90 analogous and suitable devices may be used for the purpose. It will be readily seen that if these rings were not provided a person could turn or tilt the ball-containing receptacle, so that the balls in the runway would 95 fall back into the receptacle, and then, holding the receptacle in this tilted position, with no balls in the runway, he could reciprocate the plunger as many times as desired, thus operating the registering mechanism without 100 any balls issuing from the exit end of the runway, and there would thus be a discrepancy between the number of balls actually withdrawn and the number registered by the registering mechanism. 105

A slot 41 is cut transversely through the sections 35 and 36 toward the lower ends thereof, and disposed within this slot is a reciprocatory plunger 42, provided with an opening 43 therethrough, located intermediate the ends of the plunger and slightly larger than the size, in cross-section, of the balls 23, with two end openings 44 and 70, opening 44 being conveniently adapted for the insertion of a finger therein in the operation of reciprocating the plunger and opening 70 being adapted for the insertion therethrough of a hasp 45 of a padlock or the like 110 46, thus to lock the plunger against movement when the machine is out of operation 115 and preventing fatal and unauthorized tampering therewith and with a rack portion 47 toward its rear end. The opening 43 is so disposed at a certain point in the reciprocatory plunger that it is normally out of register with the runway 38; but upon outward movement of the plunger the opening is brought into register with such runway, permitting passage of a ball therethrough. 120 125

Disposed in a mortise 48 in that face of the 130

section 35 which rests against the section 37 (and which mortise communicates with the runway 38) is a ball-actuated pivoted dog 49, the longer arm 50 whereof engages the rack 5 47 and limits forward movement of the plunger 42 and the shorter arm 71 whereof projects into the runway 38, and thus into the path of movement of the balls 23. Above the mortise 48 is another mortise 51, communicating with the runway 38 by a groove 52.

Located in the groove 52 and mortise 5, and extending transversely across the runway 38 is an auxiliary plunger 53, operated by the movement of the plunger 42 through 15 interposed mechanism (presently to be described) and having a head 54, working in the mortise 51, and also having an opening 56 therethrough slightly larger than the balls 23.

Also disposed within the mortise 51 is a coiled 20 spring 55, one end thereof bearing against the head 54 of the plunger and the other end thereof bearing against the end of the mortise 51, the effect of the spring being normally to keep the plunger 53 in the position 25 shown in Fig. 4, the opening 56 in this position of the plunger being in register with the runway 38. When the plunger 53 is moved to the position shown in Fig. 5 and the spring 55 thereby compressed, the opening 56 is 30 then out of register with the runway. Opposite the mortise 48, on the other side of the runway 38, is a mortise 57, and disposed within this mortise is a pivoted two-fingered connection or link 58, the lower finger where- 35 of engages and extends through the main plunger 42 and the upper finger whereof engages and extends through the auxiliary plunger 53. In alinement with the groove 52 is a groove 59, connecting the mortise 57 40 with the runway 38, and within which groove lies the plunger 53.

Rigidly carried by the link 58 is a bifurcated or crotched yoke 60, engaging in the crotch the inner end portion of a pin 61, 45 working in a slot 62, communicating with the mortise 56, the pin extending into a chamber 63, communicating with the slot 62 and being formed by a protecting housing 64 on the exterior face or surface of the section 35, (See 50 Figs. 1 and 6,) said pin 61 being secured to a pin 80, contacting with registering mechanism of any suitable or desired description contained in a housing 81, whereby the registering mechanism is operated at each move- 55 ment of the main plunger outward to register one ball. The operation of this portion of my device is as follows: The balls 23, being inserted in the receptacle 14, drop into the runway 38, forming a column therein. (See 60 dotted lines, Fig. 3.) In the normal position of the auxiliary plunger 53 the opening there- 65 through is in alinement with the runway 38, and there is consequently an open passage for the balls, and therefore the lowermost ball in

depressing the shorter finger 71 of the pivoted dog or pawl and throwing the longer arm 50 of the dog out of engagement with the rack 47, thus permitting reciprocation of the plunger 42, all as clearly shown in Fig. 4. 70

When it is desired to cause the exit from the runway of said lowermost ball, the plunger 42 is pulled out, (see Fig. 5,) which brings the opening 43 therein in register with the runway 38, and the ball drops through, and simultaneously the auxiliary plunger 53 is moved through the medium of the connection 58, so that the opening in the auxiliary plunger 53 is no longer in register with the runway, thereby preventing passage of any 80 ball therethrough at this point in the operation, all as clearly shown in Fig. 5. The movement of the link 58 by the plunger 42 causes the yoke 60 to depress the pin 61 in engagement with the registering mechanism, 85 thus automatically to record the passage of a ball through and out of the runway. As soon as the finger of the operator is removed from the projected or withdrawn plunger the spring 51 pushes the auxiliary plunger 53 forward, thereby rocking the link 58 and simultaneously shifting the main plunger 42 inward to normal retracted position. The cup-shaped depressions 2 afford a convenient receptacle for holding the balls as they pass out 90 of the runway, and they may thence be deposited in the chamber 3 by the proper official, such as the clerk of the court, who would in this case hold the key to and would lock the balls within the chamber 3. From 95 thence they can, by the judge of the court, be dropped into the chamber 4 through the opening 72. Within the chamber 4 is a two-fingered pawl 65, the longer finger whereof, 66, is directly under the opening 72, and therefore in the path of movement of a ball dropped or pushed therethrough, and the shorter finger 67 whereof is engaged by a coiled spring 83, the other end thereof bearing against the wall of a recess 84 in the walls 100 of the chamber 4, the effect of this spring being to keep the longer finger 66 parallel with the top of the chamber 4, said finger being depressed and the spring 67 compressed when the ball is pushed through the opening 72, 105 and as soon as the ball is released from the finger 66 the spring 83 immediately rocks the pawl to throw the longer finger thereof, 66, into normal upper position. The pawl 65 is integral with or fast on its pivot-pin 73, 110 which extends into the chamber 8, containing the registering mechanism, and contacts therewith, and this registering mechanism, of any desired or appropriate description, is actuated by movement of the pivot-pin by depression of the finger 66 by the ball as it enters the chamber 4, thus registering the deposit of the ball. The judge, who would make such deposit of the balls in the chamber 4, as removed from the chamber 3, (in which 115

latter chamber they have been deposited by the clerk,) is thus enabled to check and to tally the register of the balls as made by the clerk, it being readily understood that the registering mechanism of the clerk and that of the judge should each register the same number of balls; that the balls are numbered, as shown in the drawings; that the clerk and the judge each have a duplicate list of names of proposed jurymen, each name numbered consecutively, and that it is decided by the numbers on the balls, as each and the requisite number thereof is drawn from the receptacle, which numbers on the list are to be selected. It quite often happens that more than one list of names of jurymen are drawn up in the great cities, for instance. In this case the judge uses the registering mechanism in housing 9 as a memorandum of the number of the particular list which is being checked off. The judge being told that the clerk is working on the second list and is withdrawing balls from out the runway to check off numbers on the second list would thereupon insert his thumb or finger or other object through the opening 74, depressing the finger 75 of a pawl 76, integral with or fast on a pivot-pin 77, one end of which contacts with the registering mechanism in the chamber 9 and movement of the pivot-pin effecting operation or actuation of such registering mechanism, (in the usual and well-known manner,) the other finger 78 of the pawl being weighted to maintain it normally in vertical position. The movement of the pawl by the judge, as just described, would bring the number "2" into view on the registering mechanism, as shown in Fig. 1. As the judge and the clerk of the court each hold duplicate lists of jurymen, the judge is enabled to keep a check on the clerk and insure that he does not use one list of jurymen more than once. Each name of each juror on each list is numbered consecutively, and the balls are likewise numbered consecutively. It will thus be seen that absolute impartiality in selecting the jurymen is insured by the operation of my device, as, the receptacle 14 being of some opaque substance, such as metal, no one can tell the order of the balls as they fall therefrom into the runway, and the selection of the jurymen is thus secured, as it were, by chance.

Having thus fully described my invention, what I claim as new, and desire to secure by Letters Patent, is—

1. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

sage of more than one ball from out the exit end of the runway at one operation of the plunger.

2. In a device of the character described, a ball-containing receptacle provided with an ingress-opening and an egress or exit opening for the balls, a funnel secured around the ingress-opening, a member secured to the receptacle and provided with a runway therethrough in alinement with the exit-opening of the receptacle, a reciprocatory plunger working in the member and disposed across the runway, and means also disposed at all times across the runway for preventing passage of more than one ball from out the exit end of the runway at one operation of the plunger.

3. In a device of the character described, a ball-containing receptacle provided with an ingress-opening and an egress or exit opening for the balls, a funnel removably secured around the ingress-opening, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

4. In a device of the character described, a ball-containing receptacle provided with an ingress-opening and an egress or exit opening for the balls, a funnel secured around the ingress-opening and formed in the shape of a truncated cone, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

5. In a device of the character described, a ball-containing receptacle provided with an ingress-opening and an egress or exit opening for the balls, a tapering funnel removably secured around the ingress-opening and provided with longitudinal slits or slots dividing it into prongs or tines, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

6. In a device of the character described, a ball-containing receptacle provided with an ingress-opening and an egress or exit opening for the balls, a tapering funnel secured around the ingress-opening and provided with longitudinal slits or slots dividing it into prongs or

tines, said funnel being constructed of spring material, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

10 7. In a device of the character described, a ball-containing receptacle provided with an ingress-opening and an egress or exit opening for the balls, a removable funnel depending from the ingress-opening, means for preventing accidental displacement or movement of the funnel, a member secured to the receptacle and provided with a runway therethrough in alinement with the exit-opening of the receptacle, a reciprocatory plunger 15 working in the member and disposed across the runway, and means for preventing passage of more than one ball from out the exit end of the runway at one operation of the plunger.

20 8. In a device of the character described, a ball-containing receptacle provided with an ingress-opening and an egress or exit opening for the balls, a removable funnel depending from the ingress-opening, a closure-cap bearing 25 against the funnel, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

30 9. In a device of the character described, a ball-containing receptacle provided with an ingress-opening and an egress or exit opening for the balls, a removable funnel depending from the ingress-opening, a removable closure-cap bearing against the funnel, means 35 for preventing unauthorized removal or movement of the cap, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

40 10. In a device of the character described, a ball-containing receptacle provided with an ingress-opening for the balls, with an interiorly-threaded extension around said opening, and with an egress or exit opening for the balls, a removable funnel depending from the extension, an exteriorly-threaded, removable closure-cap screwed within the extension and bearing against the funnel, means for preventing unauthorized removal or 45 movement of the cap, a member secured to

the receptacle and provided with a runway therethrough in alinement with the exit-opening of the receptacle, a reciprocatory plunger working in the member and disposed across the runway, and means for preventing 70 passage of more than one ball from the exit end of the runway at one operation of the plunger.

11. In a device of the character described, a ball-containing receptacle provided with an 75 ingress-opening for the balls, with an interiorly-threaded extension around said opening, and with an egress or exit opening for the balls, a removable funnel depending from the extension, an exteriorly-threaded, removable closure-cap screwed within the extension and bearing against the funnel and provided with perforated offsets or lugs, said extension carrying a perforated plate, locking means passing through the perforations 80 in the lugs and the plate, a member secured to the receptacle and provided with a runway therethrough in alinement with the exit-opening of the receptacle, a reciprocatory plunger working in the member and disposed 85 across the runway, and means for preventing passage of more than one ball from out the exit end of the runway at one operation of the plunger.

12. In a device of the character described, 90 a ball-containing receptacle provided with an exit-opening for the balls, a member secured to the receptacle and provided with a runway therethrough in alinement with the exit-opening of the receptacle, a reciprocatory 95 plunger working in the member and disposed across the runway, an auxiliary reciprocatory plunger working in the member and disposed above the main plunger and extending at all times across the runway, a connection 100 between the main and the auxiliary plungers, and the plungers being provided with means so disposed that, when passage is open through the main plunger, passage through the auxiliary plunger is blocked, and vice 105 versa.

13. In a device of the character described, a ball-containing receptacle provided with an exit-opening for the balls, a member secured to the receptacle and provided with a runway 110 therethrough in alinement with the exit-opening of the receptacle, a reciprocatory main plunger working in the member and disposed across the runway, an auxiliary reciprocatory plunger working in the member 115 and disposed above the main plunger and extending across the runway, and a pivoted link, one end thereof extending through the main plunger and the other end thereof through the auxiliary plunger, the plungers 120 being so formed and disposed relative one to the other that, when passage is open through the main plunger, passage through the auxiliary plunger is blocked, and vice versa.

14. In a device of the character described, 125

- including registering mechanism, a ball-containing receptacle provided with an exit-opening for the balls, a member secured to the receptacle and provided with a runway therethrough in alinement with the exit-opening of the receptacle, a reciprocatory main plunger working in the member and disposed across the runway, an auxiliary reciprocatory plunger working in the member and disposed above the main plunger and extending at all times across the runway, a pivoted link, one end thereof extending through the main plunger and the other end thereof through the auxiliary plunger, said link carrying a yoke, and a pin, one end thereof in contact with the registering mechanism and the other end thereof being engaged by the yoke; said plungers being so formed and disposed relative one to the other that, when passage is open through the main plunger, passage through the auxiliary plunger is blocked, and vice versa.
15. In a device of the character described, a ball-containing receptacle provided with an exit-opening for the balls, a member secured to the receptacle and provided with a runway therethrough in alinement with the exit-opening of the receptacle, a reciprocatory plunger working in the member and disposed across the runway, a spring-controlled, auxiliary, reciprocatory plunger working in the member and disposed above the main plunger and extending at all times across the runway, and a connection between the main and the auxiliary plungers; the plungers being so formed and disposed relative to each other that, when passage is open through the main plunger, passage through the auxiliary plunger is blocked, and vice versa.
20. 16. In a device of the character described, a ball-containing receptacle provided with an exit-opening for the balls, a member secured to the receptacle and provided with a runway therethrough in alinement with the exit-opening of the receptacle, a reciprocatory plunger working in the member and disposed across the runway, means for limiting forward or outward movement of the plunger, and means, also disposed at all times across the runway, for preventing passage of more than one ball from out the exit end of the runway at one operation of the plunger.
25. 17. In a device of the character described, a ball-containing receptacle provided with an exit-opening for the balls a member secured to the receptacle and provided with a runway therethrough in alinement with the exit-opening of the receptacle, a reciprocatory plunger working in the member and disposed across the runway, and means, also disposed at all times across the runway, for preventing passage of more than one ball from out the exit end of the runway at one operation of the plunger.
30. 18. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger, and means for preventing the balls in the runway from escaping back to said receptacle when the same is tilted or oscillated.
35. 19. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger, and automatically-operating means for preventing the balls in the runway from escaping back to said receptacle when the same is tilted or oscillated.
40. 20. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger, and pivoted means for preventing the balls in the runway from escaping back to said receptacle when the same is tilted or oscillated.
45. 21. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger, and means, disposed in the runway, for preventing the balls therein from escaping back to said receptacle when the same is tilted or oscillated.
50. 22. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger, and means, disposed in the runway, for preventing the balls therein from escaping back to said receptacle when the same is tilted or oscillated.
55. 23. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger, and means, disposed in the runway, for preventing the balls therein from escaping back to said receptacle when the same is tilted or oscillated.
60. 24. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger.
65. 25. In a device of the character described, a ball-containing receptacle supported for oscillatory movement and provided with an exit-opening for the balls, a member secured to the receptacle and provided with a runway therethrough in alinement with the exit-opening of the receptacle, a reciprocatory plunger working in the member and disposed across the runway, means for preventing passage of more than one ball from out the exit end of the runway at one operation of the plunger.

- 5 tory plunger working in the member and disposed across the runway, means for preventing passage of more than one ball from out the exit end of the runway at one operation of the plunger, and pivoted rings in the runway, at the upper end thereof.
- 10 23. In a device of the character described, a ball-containing receptacle provided with an exit-opening for the balls, a member secured to the receptacle and provided with a runway therethrough in alinement with the exit-opening of the receptacle, and with transparent windows in alinement with the runway, whereby passage of balls therethrough may be seen, a reciprocatory plunger working in the member and disposed across the runway, and means for preventing passage of more than one ball from out the exit end of the runway at one operation of the plunger.
- 15 24. In a device of the character described, a ball-containing receptacle provided with an exit-opening for the balls, a member secured to the receptacle and provided with a runway therethrough in alinement with the exit-opening of the receptacle, a reciprocatory plunger working in the member and disposed across the runway, a pivoted dog engageable with the plunger for limiting forward or outward movement thereof, and means for preventing passage of more than one ball from out the exit end of the runway at one operation of the plunger.
- 20 25. In a device of the character described, a ball-containing receptacle provided with an exit-opening for the balls, a member secured to the receptacle and provided with a runway therethrough in alinement with the exit-opening of the receptacle, a reciprocatory plunger working in the member and disposed across the runway, a pivoted dog engageable with the plunger for limiting forward or outward movement thereof, and means for preventing passage of more than one ball from out the exit end of the runway at one operation of the plunger.
- 25 26. In a device of the character described, a ball-containing receptacle provided with an exit-opening for the balls, a member secured to the receptacle and provided with a runway therethrough in alinement with the exit-opening of the receptacle, a reciprocatory plunger working in the member and disposed across the runway, a ball-actuated, pivoted dog engageable with the plunger for limiting forward or outward movement thereof, and means for preventing passage of more than one ball from out the exit end of the runway at one operation of the plunger.
- 30 27. In a device of the character described, a hollow base, standards rising therefrom, a ball-containing receptacle mounted for oscillatory movement on said standards and provided with an exit-opening for the balls, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.
- 35 28. In a device of the character described, a base provided with depressions in its upper surface, standards rising from the base, a ball-containing receptacle mounted for oscillatory movement on said standards and provided with an exit-opening for the balls, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.
- 40 29. In a device of the character described, a base provided with an interior compartment or chamber, and having an opening in the top communicating with said interior chamber, registering mechanism within the base and actuated by deposit of a ball through the said opening in the top of the base, standards rising from the base, a ball-containing receptacle mounted for oscillatory movement on said standards and provided with an exit-opening for the balls, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.
- 45 30. In a device of the character described, a base, standards rising therefrom, a ball-containing receptacle mounted for oscillatory movement on said standards and provided with an exit-opening for the balls, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.
- 50 31. In a device of the character described, a base, standards rising therefrom, a ball-containing receptacle mounted for oscillatory movement on said standards and provided with an exit-opening for the balls, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.
- 55 32. In a device of the character described, a base, standards rising therefrom, a ball-containing receptacle mounted for oscillatory movement on said standards and provided with an exit-opening for the balls, a member secured to the receptacle and provided with a runway therethrough in alinement with the exit-opening of the receptacle, a reciprocatory plunger working in the member and disposed across the runway, and means for preventing passage of more than one ball from out the exit end of the runway at one operation of the plunger.

Witnesses:

EDGAR T. BRANDENBURG,
PHILIP SEWELL.

CHARLES A. SNYDER.

In testimony whereof I have signed my name to this specification in the presence of two subscribing witnesses.
